UNITED STATES PATENT OFFICE.

ERNEST HOLLINGS, OF CLEVELAND, OHIO.

NUT-MACHINE.

1,346,889.

Specification of Letters Patent. Patented July 20, 1920.

Application filed August 20, 1917. Serial No. 187,306.

To all whom it may concern:

Be it known that I, ERNEST HOLLINGS, a subject of the King of England, residing at Cleveland, in the county of Cuyahoga and State of Ohio, have invented certain new and useful Improvements in Nut-Machines, of which the following is a specification.

This invention relates to nut forming machines and more particularly to machines for hot forging or pressing nuts.

The object of the invention is to provide an improved machine for forming nuts from a bar by the combined action of a set of indenting, cut off, and crowning tools, and 15 piercing punches, and in which the piercing tool is quickly withdrawn from the blank after the piercing operation and before the blank is ejected from the die to prevent the nut from freezing or shrinking upon the 20 punch. A further object of the invention is to improve the arrangement of the cams, levers and other mechanism for producing such movement of the tools and punches, and to also provide an operating lever for one of 25 said tools which also serves as an oil reservoir to lubricate the machine or parts thereof.

Further objects of the invention are in part obvious and in part will appear more 30 in detail hereinafter.

In the drawings, which represent one form 35 of machine embodying the invention, Figure 1 is a longitudinal sectional elevation on the line 1—1, Fig. 2; Fig. 2 is a plan view; Fig. 3 is a sectional elevation on the line 3—3, Fig. 1, looking in the direction of the arrows; and Figs. 4, 5, and 6 are respectively a side elevation, plan and end view on a larger scale, of a rocker lever.

40 The machine shown in the drawings comprises a suitable frame 1 serving to support the bearings for three operating shafts 2, 3 and 4 provided with driving gears 5, 6 and 7, of which gears 5 and 6 intermesh with each 45 other and gears 6 and 7 mesh with a common driving gear 8 on the power shaft 9 having the belt pulleys 10.

Shaft 3 is provided with a cam or cams 11 for reciprocating the two vertically and 50 oppositely movable heads 12 carrying the indenters 13 which nick or indent the bar of stock fed along the guide 14 against the usual adjustable stop 15.

Shaft 4, at the right in Fig. 1, actuates a 55 slide 16 carrying the cut-off tool 17 for shearing the nicked blank from the bar and

carrying it into the die block 18, and a slide 19 slidable upon the slide 16 and carrying the punch 20. To actuate slide 16 shaft 4 is provided with an eccentric crank portion 21 60 operating the pitman 22 connected to said slide and which pitman therefore gives motion in both directions to said slide. The slide 19 is normally held back by a spring 23 and is advanced when necessary by two 65 cams 24, 25 upon a ring portion 26 rotating with the crank 21. The first cam 24 thins the slug in the center of the nut, while the second cam 25 ejects the slug from the cut-off tool as will later appear.

70 Shaft 2, at the left in Fig. 1, actuates a slide 27 carrying the crowning tool 28 and a slide 29 slidable upon slide 27 and carrying the piercing punch 30. Slide 27 carries two anti-friction rollers 31 which coöperate with 75 cams 32 on shaft 2 to advance said slide, and said slide is retracted either by the action of the blank entering the die or by the retreat of the piercing punch, as will appear.

Slide 29 is provided with a roller 33 coöperating with the cam 34 to advance said slide, and is retracted by the lobes 35, 36 on the sides of cam 34, which engage rollers 34^a carried by a lever 37 fulcrumed in the frame, and whose forward end is provided with a 85 projection 39 lying in advance of a shoulder 40 on the slide 29.

80 The lever 37 is a hollow forging or casting having a bottom 41 curved or sloping upward toward both ends and also provided with side walls 42 forming a chamber 43 which is filled with a suitable lubricant, such as a heavy oil. Cam 34 with its side lobes 35, 36 dips down into this oil reservoir at each revolution of the shaft and carries oil 95 to the rotating shaft and cam parts at this end of the machine.

90 The slide 27 has a depending portion 44 lying in front of a heavy bar 45 extending across the machine and backed by the pressure springs 46 which transmit the pressure to the stationary frame.

100 When the slide 27 is retracted or pushed back it encounters the bar 45 and then can only be moved back a short distance farther 105 by compressing said springs.

In describing the operation of the machine we will assume that the slide 16 is fully retracted, that shaft 4 rotates in a counter clock-wise direction, Fig. 1, and that the bar 110 of stock has just been advanced or fed one step to abut or engage the stop 15. One com-

plete cycle of operation of the machine carries each of the shafts 2, 3 and 4 through exactly one revolution.

During about the first 105° the indenters 5 operate to nick the blank and withdraw, the slide 16 in the meantime advancing toward the stock. At about 130° to 135° the cut off tool 17 shears the nicked blank from the bar and carries it into the die block against 10 the end faces of the crowning tool 28 and piercing punch 30, which move back until the springs 46 have been compressed practically to the limit. This operation compresses the blank and partially produces the 15 crown thereon.

At about 165° the cam 24 advances the punch 20 while at the same time cam 34 begins to advance the piercer 30. The two punches enter the center of the blank and 20 thin the slug to about half the thickness of the blank until at about 180° the nut has been full expanded into the die, pressed to shape and crowned. At this point the cross bar 45 has reached its seat on the stationary 25 frame so that the cut-off tool is pressing the nut against a perfectly rigid backing. The piercer 30 is now moving forward and shears the slug out, carrying it back into the hollow cut-off tool against the retreating punch 30 20 to the full limit of the operation of cam 34 at about 190°, whereupon the piercer 30 is quickly withdrawn to get it out of the hot pierced blank and prevent said blank 35 from shrinking, cooling or freezing upon the punch, as sometimes occurs with other machines not so arranged.

The piercer 30 is moved back or withdrawn from the blank by the cam 35 which oscillates the lever 37 whose projection 39 40 pulls back the shoulder 40 of slide 29.

Cam 32 now comes into action, advancing slide 27 and causing the crowning tool to eject the formed nut from the die. Said nut can be kicked off from the end of the crowning tool by a suitable kicker if desired, such 45 for example as that shown and described

in my prior application for nut blank forming machine filed Feb. 16, 1917 Ser. No. 149,120. Cam 36 then oscillates the lever 37 a second time and withdraws the slide 50 29 which is provided with a shoulder 47 coöperating with a shoulder 48 on slide 27 to produce a simultaneous retreat of slide 27. The cam 25 then advances the punch 20 to eject the slug from the cut-off tool 17, 55 and said slug may be kicked off from the cut-off tool by a suitable device, such for example as that shown in my prior application for nut machine filed April 6, 1917 Ser. No. 160,206. This completes the cycle 60 of operations of the machine.

The quick withdrawal of the piercing punch prevents injury to the tools or machine, as there is no opportunity for the blank to freeze to said tool and possibly 65 break it off or jam the machine. During the entire operation the cams are also revolving in a bath of oil in the chambered lever 37 and consequently are thoroughly lubricated.

70 What I claim is:—

1. A nut machine, comprising a die block, reciprocating tools, a cam shaft for actuating said tools, and a lever operatively connecting said shaft and tools, said lever being 75 arranged to serve as a reservoir for lubricant.

2. A nut machine, comprising a die block reciprocating tools, a cam shaft for actuating said tools, and a lever operatively connecting said shaft and tools, said lever being 80 arranged to serve as a reservoir for lubricant for said shaft.

3. A nut machine, comprising a die block, reciprocating tools, a shaft, a lever operatively connecting said shaft and tools, tool actuating cams on said shaft, said lever having a chamber carrying lubricant and said cams while rotating entering said chamber and dipping into said lubricant. 85 90

In testimony whereof I affix my signature.
ERNEST HOLLINGS.
